UNITED STATES PATENT OFFICE.

JOHN MAGEE, OF MALDEN, MASSACHUSETTS, ASSIGNOR TO MAGEE FURNACE COMPANY, OF BOSTON, MASSACHUSETTS, A CORPORATION OF MASSACHUSETTS.

PLATE FOR RANGES OR STOVES.

SPECIFICATION forming part of Letters Patent No. 752,239, dated February 16, 1904.

Application filed May 22, 1903. Serial No. 158,235. (No model.)

To all whom it may concern:

Be it known that I, JOHN MAGEE, a citizen of the United States, and a resident of Malden, in the county of Middlesex and State of Massachusetts, have invented a new and useful Improvement in Plates for Ranges or Stoves, of which the following is a full, clear, and exact description, reference being had to the accompanying drawings, forming a part of this specification, in explaining its nature.

The invention herein described relates to an improved plate for ranges and stoves. It is represented as embodied in what is known as the "top" plate of a range or stove.

It comprises a structure whereby a central portion of the plate is shaped to provide or form a section of the rim of the plate and is also formed to provide end recesses for receiving the ends of detachable rims which form ornamental continuations of the rim of the plate, the purpose of the invention being to obtain a plate which shall have a central permanent rim-section capable of being finished black, which shall extend outward sufficiently to form a salient part of the edge of the plate and which salient black section shall be flanked on either side by a rim-section capable of being finished in a contrasting color to that of the central permanent rim-section and which shall also be substantially within the outer line of said central rim-section, and thus assist in making it the salient section of the edge of the plate.

I will now describe the invention in detail in conjunction with the drawings forming a part of this specification, wherein—

Figure 1 shows the top of the stove in elevation finished with my improved rim-plate structure. Fig. 2 shows a plan view of the rim-plate detached from the stove. Fig. 3 shows a plan view of one of the detachable rims detached from the rim-plate. Fig. 4 shows a cross-section on the line 4 4 of Fig. 1. Fig. 5 shows a cross-section on the line 5 5 of Fig. 1. Fig. 6 shows a cross-section on the line 6 6 of Fig. 1.

Referring to the drawings, A represents the

top plate of a stove or range. a is a central portion upon one side thereof extending outwardly and having an integral rim a', which is slightly curved or rounded from end to end. This central integral rim-forming portion of the plate has at each end an inwardly-extending curved edge a'', which is relatively deep and which is extended around the edge of the plate toward each corner, where it forms a rounded recess a''. Below this curved edge there is preferably a wall a''. There is attached to the plate in any desired way upon each side of the central permanent rim the detachable rims B B'. These detachable rims are counterparts in reverse, and each has its inner edge shaped to follow the edge of the main plate from the end of the central permanent rim thereof to or near the end of the plate. These detachable rims are in the form of scrolls. They have the enlargements b b' at each end, which are of a size to more than fill the recesses a'' a'' in the edge of the plate upon each side of the central permanent portion of the plate, and preferably one of these enlargements extends outwardly and the other inwardly. The enlargements are flattened upon their top and are in line with the upper surface of the plate. The outer edge of the scroll is curved to varying degrees, but so as to, in effect, correspond with the curve of the central permanent rim. Each scroll-rim is represented as attached to the plate by tongues b'' b'', which extend from the enlargements to engage the under surface of the plate through holes formed in the wall and plate edge. The scroll-rims may be otherwise attached to the plate, if desired. It is preferable that they should be detachably secured in order that they may be readily removed from time to time for cleaning and polishing. They also are preferably nickel-plated.

Having thus fully described my invention, I claim and desire to secure by Letters Patent of the United States—

A plate for stoves and ranges having on one or more edges an outward-extending, central portion provided with an integral rim, the

said plate having on each side of said central portion the curved edge α^2 deepened at the end of said central portion and also at the end of the plate and adapted to receive therein the 5 enlargements of a removable rim-scroll, and rim-scrolls having said enlargements shaped upon their inner edge to fit the edge of the

plate and rounded upon their outer surfaces to correspond with the integral rim of the central portion as and for the purposes set forth.

JOHN MAGEE.

In presence of—
J. M. DOLAN,
SAUL SIPPERSTEIN.
